UNITED STATES PATENT OFFICE.

DONALD G. MCKENZIE, OF VICTORIA, CANADA.

CASH-CHANGE-GIVING DEVICE.

No. 829,417.

Specification of Letters Patent.

Patented Aug. 28, 1906.

Application filed November 17, 1905. Serial No. 287,798.

To all whom it may concern:

Be it known that I, DONALD G. MCKENZIE, a citizen of the Dominion of Canada, residing at the city of Victoria, in the Province of 5 British Columbia, Canada, have invented new and useful Improvements in Cash-Change-Giving Devices, of which the following is a specification.

My invention relates to a change-giving device designed for application to a cash-register and to be coöperative therewith, the object being to deliver from coin-magazines in the machine the correct change from any particular coin given to the salesman on his 15 indicating and recording in the machine the amount of the sale made and depressing a key corresponding to the value of the coin given to operate the change-delivery.

The device comprises a series of coin-holding magazines into which payments are made by the salesman and from which change is given as required by means of a coin-ejecting slide in the base of each magazine.

The determination of what particular coin-slides shall be projected to deliver change is under a dual control and is determined, first, by a series of locking-disks coöperative with the mechanism by which the amount of the sale made is indicated and recorded, and, 25 second, by a latch-release of such coin-slides as are necessary to make up the change from a particular coin given, which release is effected by a finger-key opposite each coin-slide. The necessity for such dual control 30 will be apparent to any one who has given the matter attention, but need not be enlarged upon here.

The release of the coin-slides by the finger-keys enables them to effect the release of a 40 change-delivery drawer beneath into which the required change falls, and the drawer is outwardly projected by a spring or springs, and the change is delivered to the purchaser.

The particular manner by which I attain 45 these results is fully set forth in the following specification and illustrated in the drawings which accompany it.

Figure 1 is a vertical section through the twenty-five-cent-coin magazine, showing 50 the coöperation of the change-delivery drawer with the coin-slides, &c; Fig. 2, a front elevation of the same magazine, showing the lock-disk by which the coin-slide is controlled from the sales-register mechanism; Fig. 3, a vertical section of a double-slide magazine wherein both coin-slides are

under the control of the sales-registering mechanism as is required for ten-cent pieces; Fig. 4, a front elevation of the same, showing the lock-disk by which such control is effected; Fig. 5, a vertical section through a magazine having a double coin-slide, one only of which is under the control of the sales-register and the other operated by the change-delivery key, which conditions are required for a five-cent magazine; Fig. 6, a plan of the coin-slides of the foregoing magazines, showing the separate latch-detents. Fig. 7 is a vertical cross-section on the line 77 of Fig. 1, showing in rear elevation the manner of connecting and operating the latches which release the coin-slides of fifty-cent, twenty-five-cent, ten-cent, and five-cent pieces. Fig. 8 shows a front elevation of the lock-disks for the foregoing magazines. Fig. 9 shows in diagrammatic front elevation the mechanism by which the sales-register shaft effects the desired movement of the lock-disk shafts. Fig. 10 shows in plan view the arrangement of the mechanism by which the sales-register effects the desired movement of the lock-disk shafts and also shows the magazines, &c., the casing being shown in section and parts thereof being broken away. Fig. 11 is a diagrammatic view showing the various cycles of movement for the various lock-disks, indicating which disks are released and which are locked of the various magazines indicated by the top row of figures for sales from twenty-five cents to one dollar, indicated by the left-hand row of figures in Fig. 1, when a one-dollar piece has been tendered in payment.

The drawings herewith show the application of the invention to a cash-register of any kind wherein the indicating and recording mechanism is operable by the rotation of a shaft, whether the indicating and recording is performed on a dial or by means of a tape or other device and whether the rotation of the shaft is effected by keys or a crank-handle, and the magazines are shown to receive and deliver coins in fifty, twenty-five, ten, and five cent pieces.

A magazine for dollars is not provided in the one illustrated, as the cash-reserve drawer below the change-delivery drawer requires to be opened for the reception and payment of bills; but in a complete machine the same principle of magazine reception and delivery may be extended to include dollars and five, ten, and twenty dollar pieces and also with

slight modifications, to the reception and payment of cents.

The front plate of the casing which encloses the register is represented by 2, the back plates by 3, the side plates by 4, and the top by 5, the upper part, within which are the coin-magazines, being provided with a glass-front plate 6, and the lower part with a cash-delivery drawer 7, and a general cash-drawer 75 below for bills, reserve cash, &c.

The coins are charged through horizontal apertures 9 (see Fig. 1) just below the top plate of the machine into cylindrical magazines 10, which may be of open or skeleton construction or be made of glass, so as to reveal the coins in each, and may be graduated to facilitate the determination of the amount and when any of these magazines are full a downwardly-curved flanged chute 11 delivers the overflow to the reserve-drawer at the bottom of the machine. These magazines 10 are socketed into the upper part 18 of a slide-frame secured between the sides 4 of the machine, and slidable in this frame under each magazine is a coin-slide 12, resting on the bottom plate 19 of the slide-frame and laterally guided by divisions 20.

In each coin-slide 12 is an aperture 13, corresponding with the circular dimension of the coin the magazine is designed to hold, and when the aperture 13 is in alignment with the bore of the magazine the bottom coin will occupy the aperture. Each slide 12 is provided with a spring 17, which tends to force the slide out from under the magazine until the aperture 13 is clear of the bottom plate 19 of the slide-frame, in which position a coin in the aperture will fall out into the change-delivery drawer 7 beneath, the bottom 8 of which is sloped downward toward the front. The back end of each coin-slide is connected by a stiffly-resilient member 31 to the upper end of a lever 32, the several levers being separately mounted free on a rod 33, which extends across and is secured to the sides 4 of the casing, and the lower ends of the lever 32 are carried down to engage and be operated by a bar 34, extending across the back of the change-delivery drawer 7, so that the outward movement of the drawer will pull back all the coin-slides that have been projected to deliver change. Each coin-slide is normally held in the backward position with its aperture in axial alignment with the bore of its magazine by a latch 21, pivotally mounted at 22 on the slide-frame 18 and pressed into a notch 15 in the edge of the slide by a spring 25. This latch 21 is released from engagement with the notch 15 of the coin-slide by the inner end of a finger-key lever 35, pivotally mounted on the slide-frame 18 or in the casing of the machine, the end of which lever passes under a projection 24 of the latch, so that the depression of the finger-key will pull the latch out of the notch

of the slide, leaving the slide free to be thrown forward by its spring 17.

The change-delivery drawer 7 is projected outward when required by a spring or springs 36, secured to the drawer and to the front casing-plate 2 of the machine, and is normally retained in the closed position by latches 37, pivotally mounted at 38 on each side casing 4 and engaging notches 40 in the sides of the drawer. These latches 37 are connected together by a bar 39, extending between them and so placed that it will be engaged by the lower end of any coin-slide lever 32 as it flies back when a coin-slide is released and will lift the latches 37 from the notches 40 and allow the drawer to fly out under the influence of its springs 36.

The foregoing description applies generally to a single-slide magazine, such as is used for fifty and twenty-five cent pieces; but the same general construction applies to the ten and five cent magazine-slides; but as in giving change two ten-cent pieces or one ten-cent piece may be required at certain times the ten-cent magazine is provided with two slides superposed and operable in a similar manner. The determination of whether the release of one or both slides is to be effected is determined by the lock and release mechanism under control of the sales-register in a manner to be described later. The five-cent magazine is also provided with two slides; but the operation of their release is under separate control and will be described later.

On reference to Fig. 7 it will be seen that the latches of the several magazines' coin-slides are co-operative together, the upper ends being connected by pins 23 to latch-bars 26 and 27, extending between them and having a spring 30 to hold the combined mechanism in the latched position. Thus the depression of the highest-value finger-key, which is marked "\$1," as it is to be depressed when one dollar is tendered in payment and from which change is required, will release the coin-slides of all the magazines of less value. Similarly the fifty-cent key next to it will effect the release of the detents from the slides of all the magazines of less value, but will not release the one higher, as the bar 26, which connects to its latch, is provided with a backwardly-elongated slot 28. Similarly the twenty-five-cent key will release both ten-cent slides and one of the five-cent slides; but as the bar 27, connecting it to the twenty-five-cent latch, is provided with a backwardly-elongated slot 29, it will not release the twenty-five or fifty cent latches.

It will be noticed that the latch of the lower five-cent slide only is released by the connected mechanism just described, the edge of the upper slide 16 (see Fig. 6) being cut away, as at 41, to the depth of the notch to permit the top slide to pass when the latch 21 may be in engagement with its notch 15 in

the lower slide. The upper plate is latched and released directly by a backwardly-bent and downwardly-turned extension 42 of the finger-key of the ten-cent magazine, which 5 engages a notch 43 in the opposite edge of the top slide 16. This provision of two slides for the five-cent magazine, one to be operated by the general latch-release mechanism and the other operated directly by the ten-cent 10 finger-key, is rendered necessary because on registration of a five-cent sale the lock-disk which controls the slide requires to be in the locked position while a ten-cent payment 15 may be made necessitating the delivery of five-cent change.

Although the depression of the finger-key levers 35 effects the release of the latches of all the magazine coin-slides of lower value than the one depressed and leaves the slides 20 free to be projected outward to discharge the coin which occupies the aperture 13 thereof, a further control of the coin-slides is required to insure that the correct slides only are projected to give the required change, and this 25 control must work in conjunction with the mechanism which announces and registers the amount of the sale made. It is immaterial what particular cash-register is employed so long as either the sales announcer or register of it is operable by a shaft rotatable by 30 any means.

On referring to Fig. 9, 45 represents the shaft by which the registering mechanism is operated, and we will assume that one revolution of the shaft 45 will announce and register whether by dial or tape sales progressing from five cents to a dollar. On considering when the various coin-slides should be projected to give change for various sales 35 from five cents to a dollar and when locked to prevent such projection it is found that the periods of lock and release follow a certain cycle in the progressive sales. I therefore provide in front of each coin-slide a lock and 40 release disk 46, rotatable on shafts 47 48 49 45 50 below it in such a position that the upper part of the periphery of the disk is in front of a downward projection 14 from the front edge of each slide. These disks are rotatable 45 50 by suitable gearing from the shaft 45 of the sales-register, so that the period of their rotation corresponds with that of the cycle of lock and release required for each magazine-slide, and the periphery of the disk is provided 55 with notches which will permit the passage of the projection 14 in the order required in each cycle. Thus the five-cent coin slide for a five-cent sale should be locked, (L,) for a ten-cent sale the slide should 60 be released (R) to be projected, for a fifteen-cent sale locked, (L,) for a twenty-cent sale released, (R,) for a twenty-five cent locked, (L,) and this cycle of lock (L) released, (R,) lock (L) released, (R,) lock (L) is repeated again 65 from thirty to fifty, from fifty-five to sev-

enty-five, and from eighty to one hundred. (See diagrammatic Fig. 11.) The shaft 47, on which is secured the lock and release disk for the five-cent-magazine slide, is therefore caused to perform four revolutions to 70 one of the sales-register shaft 45, because the cycle of its lock and release recurs four times in the sales from five cents to a dollar, and the periphery of the disk 46 is divided into five equal parts corresponding with the 75 five divisions of the cycle and has notches 51 recurring in the rotation required by the cycle, as illustrated in Fig. 8, where the radiating lines indicate divisions of the disk, and the cycle of lock and release is attained by 80 the order of recurrence of the notches 51 in the periphery of the disk.

In considering the requirements of lock and release of the ten-cent-magazine coin-slides we have to deal with the possibility of one or 85 two ten-cent pieces being required to make up change, for which purpose the two superposed coin-slides are provided, and to enable one or both to be released, as occasion may require, the lower one has a downward projection 52 larger than that, 14, of the upper one. Smaller and larger notches 57 or 58 in the lock-disk provide for the release of both or one slide in the proper order required by the cycle, which, examination shows, to be for 90 a five-cent sale both may require to be released, for a ten-cent sale release one, fifteen cents release one, twenty cents lock, twenty-five cent lock, the cycle as before recurring four times in sales from five cents to a dollar. 100 The period of rotation of the ten-cent lock-shaft 48 should therefore be the same as that of the five-cent shaft—namely, four to one of the sales-register shaft.

For a twenty-five-cent magazine the cycle 105 of lock and release recurs twice in the sales from five cents to a dollar, from five to twenty-five requiring to be free, and from thirty to fifty locked, this cycle being repeated from fifty-five cents to one dollar. Therefore its 110 disk-shaft 49 may be rotated at the same speed as the sales-register shaft, and the first quarter of its periphery, in which the slide requires to be free, is removed, as at 53, to permit the passage of the downward projection 14 of the slide, the second quarter is 115 intact, as at 54, the third quarter removed, and the fourth quarter intact.

For a fifty-cent magazine the slide requires to be free from five cents to fifty and 120 locked from fifty-five to a dollar. Therefore if its lock-disk shaft 50 is rotated at the same speed as the register-shaft 45 the periphery of the disk throughout one half of the circumference may be removed, as at 55, and 125 for the other half left intact, as at 56.

Fig. 8 shows the correlative positions of the lock and release disks of the several magazine-slides, (represented as at zero,) in which position all the slides are locked, the dot-and-

dash radial lines indicating the divisions of the disks corresponding to registered sales progressing by five cents to a dollar. Thus if the register-shaft 45 is turned one-twentieth of a revolution as indicating a five-cent sale the shaft 47 and 48 will rotate one-fifth of a revolution and the shafts 49 and 50 one-twentieth of a revolution in the direction indicated by the arrows, in which position the five-cent disk on the shaft 47 will still be in the locked position and the notch 58 and the removed portions 53 and 55 will be brought to the top opposite to the downward projections 14 52 of the respective coin-slides, so that if five cents is paid to cover the five-cent sale no change can be withdrawn; but if ten cents is paid to cover it the key 35 of the ten-cent magazine is depressed and the upper slide of the five-cent magazine is released and projected, as the top five-cent slide is not dependent on the lock and release disk, the five cents change being dropped into the delivery-drawer and outwardly projected. If a dollar is paid to cover the five-cent sale, the dollar is deposited in the cash-reserve drawer unless a dollar-magazine is furnished and the finger-key 35 marked "S1" is depressed, which releases all the coin-slides, and as all the disks but the five-cent one are set to release the slides they will be projected and will drop into the delivery-drawer one fifty-cent piece, one twenty-five-cent piece, and two ten-cent pieces, making the required change of ninety-five cents.

Now assume that a seventy-five cent sale is registered. That means that the shaft 46 is rotated through three-quarters of its revolution. The lock and release shafts 47 and 48 will each make three revolutions and return to the positions indicated on the drawing--namely, locked--the shafts 49 and 50 will be rotated through three-quarters of a revolution, which will bring a removed space 53 of the disk of the 49 shaft opposite to the downward projection of the slide, and its slide will be free for release and the disk of the shaft 50 will have an intact part 56 opposite to the downward projection 14, and its slide will be locked. If now a dollar payment is made and the dollar finger-key depressed, all the coin-slides will be released by the latches 21; but only the slide of the twenty-five-cent magazine will be free to pass its lock and release disk, and twenty-five cents change will be dropped into the delivery-drawer.

Figs. 9 and 10 show the arrangement of the gear-wheels, by which the rotation of the several lock and release shafts is effected from that of the announcing and register shaft 45. A wheel 60, secured on the register-shaft, meshes with a pinion 61 of the required diameter on the shaft 47 for the five-cent-magazine lock. The shaft 48 for the ten-cent magazine being driven at an equal

speed to 47 is rotated from it by equal wheels 62 on each. A pinion 63 on the shaft 48 meshes with the wheel 64 on the shaft 49, and the shaft 50 is driven from 49 by equal wheels 65. As this mechanism requires to be returned to zero at the conclusion of each sale, the shaft 45 is rotated against the resistance of a clock-spring 66, secured to it.

The registering device of the machine may be pawl or clutch driven on the shaft 45 and provided with check-pawls to prevent its return when the change mechanism returns to zero after each sale. As it is desirable that the lock and release operating mechanism be retained in the position to which it has been moved to announce and register a given sale until the change-delivery drawer is projected out, this is effected by a pawl-wheel 68, secured on the shaft 47, and a spring-actuated pawl 69, pivotally mounted on the front plate 2 of the case, which will retain the shaft in the desired position against backward rotation. The ratchet-wheel 68 is furnished with five teeth, so that it will check the register-shaft at each five-cent division of its dial or tape. The pawl 69 is extended beyond its pivot and carried down to engage a wedge-shaped projection 70 on the edge of the change-delivery drawer 7, beneath which projection is so placed as to effect the release of the pawl when the change-delivery drawer is at the outward limit of its movement.

In the use of the device the operator rotates the sales-register shaft 45 to announce and register the amount of the sale made, and in doing so the several shafts on which the lock and release disks 46 are secured are rotated by the train of gears to lock or retain the several coin-slides, as required by such sale. The operator on receiving the coin necessary to cover the amount of the sale passes it through one of the slits 9 corresponding to its value, when it falls into the magazine 10 belonging to it, or if the magazine is full passes down the chute 11 into the back of the cash-reserve drawer. The operator then depresses the finger-key 35 corresponding to the value of the coin received, which releases the latches of all the coin-slides of less value, and such of them as are required, according to the determined cycle of lock and release of the disks 46, to make up the required change will be projected outward and will withdraw from the magazines the coins necessary and drop them into the delivery-drawer 7, which is released by the forward movement of the coin-slides operating the lever 32 to lift the drawer-latch 37. The outward movement of the drawer 7 by means of the cross-bar 34 engaging the lower end of the levers 32 will draw back the coin-slides beneath the magazines, ready for the next delivery, and when the drawer is pushed in it is automatically locked by the latch 37, and the machine is ready for a further sale.

- Having now particularly described the invention and the manner of its operation, I hereby declare that what I claim as new, and desire to be protected in by Letters Patent, is—
1. A change-giving device of the character stated, comprising the combination with a rotatable shaft, of a coin-magazine, a spring-actuated coin-ejecting slide at the base thereof, a latch for normally retaining said slide in alinement with the bore of the magazine, means coöperative with the rotatable shaft for controlling the ejection of the slide according as the amount of the sale may require change from the magazine, and means for releasing the latch and the slide. 5
2. In a device of the class described, the combination with a rotatable shaft, of coin-magazines, means for directing the coins into the magazines, said means including a horizontal coin-receiving slot, a flanged overflow-chute downwardly curved from the top of each magazine opposite to the coin-slot, means for ejecting coins from the magazine, rotatable means for holding the ejecting means from operation, and means coöperatively connecting the rotatable shaft with the rotatable holding means for controlling said holding means, substantially as shown and described. 15
3. In a device of the class described, the combination with a rotatable shaft, of vertically-disposed cylindrical coin-holding magazines having closed lower ends, spring-controlled coin-ejecting slides for said magazines, a latch for retaining each slide in alinement with the bore of its magazine, means for releasing said latch, and means coöperative with the rotatable shaft for controlling the operation of the coin-slides according as change is required or not, substantially as shown and described. 30
4. In a device of the class described, the combination with a rotatable shaft, of coin-holding magazines having independent spring-actuated coin-ejecting slides, latches for retaining each slide in alinement with the bore of its magazine, means for independently releasing any latch, and means coöperative with the rotatable register-shaft for controlling the ejection or retention of the lower coin-slide as required. 45
5. In a device of the class described, the combination with a rotatable shaft, of a coin-holding magazine having two independent spring-actuated coin-slides, a latch for retaining these slides in the position of alinement with the bore of the magazine, means for releasing the latch, and means coöperative with the rotatable shaft of the register for permitting one or both of the slides to be ejected as the amount of the sale may require. 55
6. In a device of the class described, the combination with a rotatable shaft, of a series of coin-holding magazines having spring-actuated coin-ejecting slides, latches to re-
- tain such slides in alinement with the bore of their magazines, finger-keys to release the latches, and means for connecting the several latches so that the release of one will effect the release of all the others of lower value but will not effect the release of the higher-value slides. 70
7. In a device of the class described, the combination with a rotatable shaft, of a series of coin-holding magazines having spring-actuated coin-ejecting slides, means coöperative with the rotatable register-shaft for controlling the ejection of the coin-slides, such means comprising a disk rotatable below each slide, the upper part of each disk projecting in the path of a downward projection from its slide and having portions removed from its periphery at intervals that will allow the downward projection of the slide to pass, the recurrence of the removed portions corresponding to the order in which coin will be required from the magazine to make change for progressive sales indicated by intervals of rotation of the register-shaft and means for rotating the disks from the rotatable shaft of the register. 75 80 85 90
8. In a device of the class described, the combination with a rotatable shaft, of a series of coin-holding magazines having spring-actuated coin-ejecting slides and latches for retaining the slides in alinement with the bore of their magazines, a change-delivery drawer beneath the magazine having a spring by which it is forced outward, latches by which the drawer is retained in the inward position against the resistance of the spring, means for releasing the latches of the coin-ejecting slides of the magazines, means coöperative with the coin-slides for releasing the latches of the change-delivery drawer, means coöperative with the outward movement of the drawer for restoring the coin-ejecting slides to alinement with their magazines, and means coöperative with the rotatable register-shaft for controlling the rejection or retention as required of the several magazine coin-slides. 95 100 105 110
9. In a device of the class described, the combination with a rotatable shaft, of a series of coin-magazines having coin-ejecting slides, a latch-retained change-delivery drawer beneath the magazines having a spring to outwardly project it when required, latches to retain it in the inward position, means for releasing the latches of the coin-ejecting slides, means by which the ejection of a slide will effect the release of the latches of the change-delivery drawer, means by which the outward movement of the drawer will return the coin-slides of the magazines to the alinement of the bore of their magazines, means coöperative with the register-shaft for controlling the ejection of the coin-slides of the several magazines, means for retaining such coöperative mechanism in the position 115 120 125 130

to which it is set to announce or register a given sale, and means coöperative with the change-delivery drawer for releasing such retaining means and permitting the mechanism to return to zero.

10. In a device of the class described, the combination with a rotatable shaft, a series of magazines, coin-ejecting slides therefor having downward projections, means for ejecting the slides, means coöperative with the rotatable shaft for controlling the ejection and retention of the slides, said means comprising a rotatable disk beneath each slide, the intact periphery of which projects in the path of a downward projection on the coin-slide, said disk having peripheral notches to permit the downward projection of the coin-slide to pass, the peripheral notches being at intervals apart around the disk, the order of their recurrence corresponding to the order in which change is required from the magazine, and means for rotating the disks from the rotatable shaft in a period corresponding to the cycle in which change is required.

11. In a device of the class described, the combination with a rotatable shaft, of a plurality of coin-magazines, coin-slides beneath said magazines for ejecting the coins at times, locking devices for all of said slides, means for unlocking predetermined coin-slides at times and means controlled by the movement of said rotatable shaft for permitting the release of predetermined coin-slides, means for moving said coin-slides to eject the coins, substantially as shown and described.

12. In a device of the class described, the combination with a rotatable shaft, of a plurality of coin-magazines, coin-slides beneath said magazines for ejecting the coins at times, locking devices for all of said slides, means for unlocking predetermined coin-slides at times, means controlled by the movement of said rotatable shaft for permitting the release of predetermined coin-slides, means for moving said coin-slides to eject the coins, and means for returning all of said parts to their normal positions, substantially as shown and described.

13. In a device of the class described, the combination with a rotatable shaft, of a plurality of coin-magazines, coin-slides beneath said magazines for ejecting the coins at times, locking devices for all of said slides, means for unlocking predetermined coin-slides at times, means controlled by the movement of said rotatable shaft for permitting the release of predetermined coin-slides, means for moving said coin-slides to eject the coins, and a normally locked coin-receiving drawer, releasable by the movement of said coin-slides substantially as shown and described.

In a device of the class described, the

combination with a rotatable shaft, of a plurality of coin-magazines, coin-slides beneath said magazines for ejecting the coins at times, locking devices for all of said magazines, means for unlocking predetermined coin-slides at times, means controlled by the movement of said rotatable shaft for permitting the release of predetermined coin-slides, means for moving said coin-slides to eject the coins, a normally locked coin-receiving drawer, releasable by the movement of said coin-slides, and means controlled by the movement of the coin-receiving drawer for returning the parts to their normal positions, substantially as shown and described.

15. A device of the class described, the combination with a rotatable shaft, of a coin-magazine, a spring-actuated coin-ejecting slide beneath said coin-magazine, a latch for normally retaining said coin-ejecting slide in alignment with the magazines, means coöperative with the rotatable shaft for controlling the ejection of the slide to release the same at predetermined times, and manually-operated means for releasing the latch of the slide.

16. In a device of the class described, the combination with a rotatable shaft, of coin-magazines having coin-admitting slots, a flanged overflow-chute for each magazine, means for ejecting coins from the magazine at predetermined times, latches for retaining said ejecting means, and means coöperatively connected with the rotatable shaft for automatically controlling said ejection, and means for manually releasing said latches at times, substantially as shown and described.

17. In a device of the class described, the combination with a rotatable shaft, of a plurality of coin-magazines, a casing for inclosing said magazines and said shaft, said casing having slots communicating with the magazines through which coins may be deposited in the magazines, overflow-chutes for said magazines, means for ejecting coins from the magazines, means coöperatively connected with the rotatable shaft for automatically controlling such coin ejection, and a normally locked coin-receptacle releasable by the movement of the ejecting means substantially as shown and described.

18. In a device of the class described, the combination with a rotatable shaft, of a plurality of coin-magazines, a casing for inclosing said magazines and said shaft, said casing having slots communicating with the magazines through which coins may be deposited in the magazines, overflow-chutes for said magazines, means for ejecting coins from the magazines, means coöperatively connected with the rotatable shaft for automatically controlling such coin ejection, a normally locked coin-receptacle releasable by the movement of the ejecting means, latch devices for normally locking said ejecting

means, and manually-controlled means for releasing a predetermined number of said latch devices, substantially as shown and described.

19. In a device of the class described, the combination with a rotatable shaft, of vertically-disposed cylindrical coin-holding magazines, having closed lower ends, spring-controlled coin-ejecting slides for said magazines, latch devices for retaining each slide in alinement with the bore of its magazine, means for releasing said latch devices, and means co-operatively connected with the rotatable shaft for controlling the ejection and retention of the coin-slides to release or retain predetermined slides, substantially as shown and described.

20. In a device of the class described, the combination with a rotatable shaft, of coin-holding magazines, independent spring-actuated coin-ejecting slides for said magazines, latches for retaining each slide in alinement with the bore of its magazine, manually-controlled means for releasing predetermined slides, and means co-operatively connected with the rotatable shaft for controlling the ejection and retention of said slides, substantially as shown and described.

21. In a device of the class described, the combination with a rotatable shaft, of a coin-holding magazine, a pair of independent spring-actuated coin-ejecting slides therefor, latch devices for retaining each of said slides in alinement with the bore of its magazine, means for independently releasing either of said latches and means co-operatively connected with the rotatable shaft for controlling the ejection or retention of one of said slides, substantially as shown and described.

22. In a device of the class described, the combination with a rotatable shaft, of a coin-holding magazine, a pair of independent spring-actuated coin-ejecting slides therefor, latch devices for retaining each of said slides in alinement with the bore of its magazine, means for independently releasing either of said latches, and means co-operatively connected with the rotatable shaft for controlling the ejection or retention of said slides, substantially as shown and described.

23. In a device of the class described, the combination with a rotatable shaft, of a coin-holding magazine, two superimposed independent spring-actuated coin-slides therefor, a latch for retaining both of said slides in the normal position in alinement with the bore of the magazine, means for releasing said latch and means co-operatively connected with the rotatable shaft for predeterminedly releasing one or both of said slides to permit the same to be ejected substantially as shown and described.

24. In a device of the class described, the combination with a rotatable shaft, of a se-

ries of coin-holding magazines, spring-actuated coin-ejecting slides for said magazines, latches for retaining said slides in their normal positions in alinement with the bore of their magazines, finger-keys for releasing said latches and means for connecting the several latches to permit the release of one of said latches to effect the release of all other latches of lower value without effecting the release of those of higher-value slides, substantially as shown and described.

25. In a device of the class described, the combination with a rotatable shaft, of a plurality of coin-holding magazines of different denominations, spring-actuated coin-ejecting slides for each of said magazines, latch devices for locking each of said slides, a plurality of means for operating said latches, said means being arranged so that when one of said means is operated, all latches of lower denomination will be released without releasing those of higher denomination, substantially as shown and described.

26. In a device of the class described, the combination with a rotatable shaft, of a series of coin-holding magazines, spring-actuated coin-ejecting slides for said magazines, means operatively connected with the rotatable shaft for automatically controlling the ejection of said coin-slides, said means comprising rotatable disks arranged to project in the path of movement of said slides, said disks having portions removed from their periphery at predetermined intervals to allow the release of said slides when in alinement therewith substantially as shown and described.

27. In a device of the class described, the combination with a rotatable shaft, of a series of coin-holding magazines, spring-actuated coin-ejecting slides for said magazines, means operatively connected with the rotatable shaft for automatically controlling the ejection of said coin-slides, said means comprising rotatable disks arranged to project in the path of movement of said slides, said disks having portions removed from their periphery at predetermined intervals to allow the release of said slides when in alinement therewith, the recurrence of the removed portions corresponding to the order in which the coin will be required from the magazine to make change for progressive sales indicated by intervals of rotation of the rotatable shaft, and means for rotating the disks from the rotatable shafts, substantially as shown and described.

28. In a device of the class described, the combination with a rotatable shaft, of a series of coin-holding magazines, spring-actuated coin-ejecting slides therefor, latches for returning the slides in proper alinement with the magazines, a change-delivery drawer beneath the magazines, spring devices for forcing such drawer outwardly, latch devices for

locking the drawer in its closed position, means for releasing the latch devices of the coin-ejecting slides of the magazines, means coöperative with the coin-slides for releasing 5 the latches of the drawer, means coöperative with the drawer to restore the coin-ejecting slides to their normal position as the drawer moves outwardly, and means coöperative with the rotatable shaft for controlling the 10 ejection and return of the coin-slides, substantially as shown and described.

29. In a device of the class described, the combination with a rotatable shaft, of spring devices for returning said shaft to its normal 15 position, a series of coin-magazines, coin-ejecting slides for said magazines, latches for said coin-ejecting slides, a change-delivery drawer beneath the magazines, spring devices for outwardly projecting said drawer at 20 times, latches to normally retain the drawer in its inward position, means for releasing said coin-ejecting slides latches, means controlled by the movement of the slide for releasing the latches of the drawer, means controllable by the outward movement of the 25 drawer for returning the coin-slides to their normal positions, means coöperative with the rotatable shaft for controlling the ejection of the coin-slides, means for retaining said 30 operative mechanism in the position to which it is first set, and means coöperative with the change-delivery drawer for releasing said retaining means to permit the mechanism to return to its normal position, substantially as 35 shown and described.

30. In a device of the class described, the combination with a rotatable shaft, a series of magazines, coin - ejecting slides therefor, means for ejecting said slides, means coöperative with the rotatable shaft for controlling the ejection or retention of the slides, said 40 last-named means comprising a disk rotatable beneath each slide, the said disk having peripheral notches, said slides having projections for engaging the intact portion of the 45

periphery of the disks, said notched portions of the disks permitting the passage of the slide projections at times, and means coöperatively connected with the rotatable shaft and the rotatable disks for rotating said 50 disks through predetermined arcs to bring the notched portions of the disk peripheries in alinement with the projecting portions of the slides at times, the order of recurrence corresponding to the order in which change is 55 required from the magazines for progressive sales on the register.

31. In a device of the class described, the combination with a rotatable shaft, a series of magazines, coin-ejecting slides therefor, 60 means for ejecting said slides, means coöperative with the rotatable shaft for controlling the ejection or retention of the slides, said last-named means comprising a disk rotatable beneath each slide, the said disk having 65 peripheral notches, said slides having projections for engaging the intact portion of the periphery of the disks, said notched portions of the disks permitting passage of the slide projections at times, and means coöperatively connected with the rotatable shaft and the rotatable disks for rotating said disks through predetermined arcs to bring the 70 notched portions of the disk peripheries in alinement with the projecting portions of the slides at times, the order of recurrence corresponding to the order in which change is 75 required from the magazines for progressive sales on the register, said connections between the rotatable shaft and the disks being 80 arranged to rotate the disks in a period corresponding to the order in which change is required.

In testimony whereof I have signed my name to this specification in the presence of 85 two subscribing witnesses.

DONALD G. MCKENZIE.
